UNITED STATES PATENT OFFICE.

ARTHUR DAVIS, OF EVANSTON, ILLINOIS, ASSIGNOR TO MARSHALL FIELD & COMPANY,
A CORPORATION OF ILLINOIS.

TRUNK.

1,012,606.

Specification of Letters Patent. Patented Dec. 26, 1911.

Application filed January 3, 1911. Serial No. 600,514.

To all whom it may concern.

Be it known that I, ARTHUR DAVIS, a citizen of the United States, residing at Evanston, in the county of Cook and State of Illinois, have invented certain new and useful Improvements in Trunks, of which the following is a specification.

My invention relates to trunks or sample cases for the use of traveling salesmen who take with them a great variety of small articles of merchandise.

The object of my invention is to provide a trunk of this character which will permit the arrangement and disposal of the articles in a manner that will enable the salesman to have complete access to all the articles at a moment's notice; which will permit him to display them very quickly and effectively; and which will have great carrying capacity for the articles.

The above objects and others will be made more apparent in the following specification, taken in connection with the accompanying drawings and the novel elements and combinations thereof will be more particularly set forth in the claims.

In the drawings: Figure 1 is a perspective view of the trunk with the doors in an open position and a number of the merchandise holding elements removed. Fig. 2 is a vertical sectional view of the trunk. Fig. 3 is a perspective view of one of the merchandise holding elements. Fig. 4 is a cross section of a portion of one of said elements showing details of its construction. Fig. 5 is a detail showing one of the lower corners of one of said elements. Fig. 6 is a horizontal section of the body of the trunk taken on the line 6—6 of Fig. 2. Fig. 7 is a perspective view of one of the yieldable pivot pins carried by the merchandise holding elements. Fig. 8 is a perspective view of an upper corner of one of the elements.

I accomplish the object of my invention by means of the plurality of movable merchandise holding elements 11, which are supported in the trunk body 10 in such a manner that they may have a combined rotary and bodily movement. It is very desirable that a large number of these holding elements be provided in the trunk. In order to arrange them in such a manner that they may be conveniently swung about without interfering with each other, for the display of the goods, a supporting device for their

pivots is necessary which permits a bodily or sliding movement. The supporting means for said pivots constitutes an important feature of my invention and will be more fully described later.

I preferably construct the trunk body 10 with two adjacent fixed sides or walls, to which at the outer edge are pivotally attached the lids or covers 12 and 13. These lids or covers meet at one of the longitudinal edges of the trunk and are provided with suitable interlocking and fastening devices 12^a, 12^b, 12^c, 12^d, 12^e, 13^a, 13^b, 13^c, 13^d, 13^e, 13^f, &c., which are commonly employed in trunk construction. On one of the lids 13 I provide a suitable locking member 13^g which makes connections with a coöperating locking member on the lid 12.

The supporting devices for the previously mentioned merchandise holding elements 11 comprise plates 14 and 15, preferably of metal, which are fixed to the inner walls of the trunk above and below the said holding elements 11. These plates 14 and 15 are preferably given a substantially triangular form and are provided with a series of slots 16 of varying lengths having offset portions 17 and 18 at their ends. These slots are designed to receive the ends of pivot pins 19 and 20 which are attached to the merchandise holding elements 11 at upper and lower corners of the same. The purpose of these slots is to permit the elements 11 being swung from their closed positions in the trunk to open positions without interfering with each other. These slots permit a bodily movement of the elements 11 to such positions as will permit their being swung around to wide open positions without the inner edges or corners of the frames of the elements becoming wedged upon each other. This wedging action would prevent any considerable degree of opening of the elements. Two of the elements 11 are shown in Figs. 1 and 6 in their wide open positions, and four of them are shown in their closed positions.

In Figs. 1 and 6 some of the intermediate elements have been removed. In order to permit easy removal of the elements from the trunk when it is desired to more fully display the goods carried by them, or to remove said goods or attach a new supply, one of the pivot pins 19 is made yieldable, in order that it may be withdrawn from

its slot 16 in the plate 14. This is accomplished by loosely fitting said pin in the apertures in the lugs, or guides 21-22, fixed to the frame of the element 11. A shoulder 5 or projecting portion 23 is fixed to said rod or pin 19, and between the shoulder 23 and the lug 21 is placed a spring 21 whose tension normally tends to push the shoulder 23, and hence the pin, upwardly or toward the 10 lug 22. The spring is preferably a helical spring and the shoulder 23 is preferably a disk or washer fixed to pin 19.

The pivot pin 20 at the lower corner of the element is carried by the lug 25, which 15 is rigidly attached to the corner of the frame of said element and is provided with extensions 27, which are fixed to said frame and serve to strengthen it at its corners. A similar arrangement is shown at 27^a at the upper 20 corner of said frame. The pin 19 is provided with a right-angularly disposed portion 26 at its lower end, which serves as a convenient handle by which the pin may be drawn downwardly out of the slot 16 25 when it is desired to remove the element from the trunk.

The elements 11 are further supported when in their closed positions by the bar 28 having a horizontal portion lying in the 30 same plane with the plate 15 and having vertical portions 29 and 30 by which it is attached to the walls of the trunk. When the trunk is closed and being transported from place to place the weight of the elements 11 is partly carried by the plate 15 at the bottom and partly by the bar 28. The bar 28 also serves in a measure to guide the elements and to hold them in their proper vertical positions while they are being 40 moved out into their open positions. Without the bar 28 there would be a tendency of the elements 11 to tilt and care would have to be taken when opening the elements to prevent binding or interference thereof 45 with the plates 14 and 16. This tilting would be free to take place while the elements are in their closed positions, because of the fact that the planes of the elements are then substantially parallel to the slots 50 16. When the elements are at right angles to the said slots, however, the tendency to tilt in the planes of said elements does not exist.

The offsets 17 in the slots engage the pivot 55 pins 19 and 20 when they are pushed back into said offsets and assist in holding the elements rigidly in place when the trunk is closed and prevent their moving about therein. The offsets 18 serve as convenient 60 means for holding the pivot pins 19 and 20 in their proper positions while the elements are being opened. The user of the trunk is able to move the elements outwardly to the ends of the slots after which he pushes 65 them into the offset 18. The offsets 18 then

serve to retain the element in their proper opened positions.

In Fig. 4 is shown a detail of the construction of the framework of the elements 11. This framework is preferably composed 70 of strips 31-31^a of wood. Between these strips is placed a coarse wire netting 32, the edges of said netting having a position between the strips. On each side of the netting 32 is placed a sheet of suitable fabric 75 33-34. This fabric is tightly drawn in place and may be glued or otherwise secured to the netting. This fabric provides a convenient means to which may be attached articles of merchandise by means of pins, hooks, or other suitable devices. The edges of the fabric 33-34 and of the netting 32 are rigidly held in place between the strips 31-31^a by means of the screws 35 which draw the said strips tightly toward 80 each other. The outer edges of the netting in the fabric at the corners are preferably cut away, as shown at 36 and 37, in order that the frame may be more solid and substantial at these points. 90

The trunk body is made with a lower compartment 38 which is partly inclosed within four walls of the trunk, the lower part of which is not provided with doors. The compartment 38 is partly covered by the doors 95 12 and 13, the walls 39 and 40 having a vertical height equal to substantially half the depth of the said compartment. In this compartment I place telescopes or other containing elements, preferably two in number. 100 One of these telescopes will lie within the space included within the four walls while the other will occupy the space behind the lower edges of the doors 12 and 13. The purpose of this arrangement is to permit 105 one of the telescopes to be withdrawn from the compartment by sliding it over the upper edge of one of the side walls after which the lower telescope may be raised to this position and removed in the same manner. In 110 order to permit easy raising of the lower telescope to the said level I provide lifting straps 43 and 44 which are fixed to the side walls of the trunk at one of their ends and which may overlap the upper edges of the 115 two low side walls at their other ends. The middle portion of these lifting straps should lie upon the floor of the trunk as clearly shown in Fig. 1.

The telescopes are indicated in Fig. 2 by 120 the reference numerals 41 and 42. These telescopes are shown in section and are preferably two in number, but any other number that may be found convenient may be used. In case any other number is used it is 125 necessary only that the space above the lower side walls 39 and 40 be sufficient to permit the removal of one of the telescopes only. This telescope is withdrawn through the space between the upper edge of the side 130

wall 39 and the horizontal portion of the supporting bar 28. Spacing ribs 45 are arranged upon the walls of the compartment to properly hold the telescopes in place and to permit their easy removal.

5 In the use of my improved trunk for carrying merchandise, as above described, it will be seen that the two doors 12 and 13 are hinged upon diagonally opposite edges of the trunk body and that adjacent sides of the trunk are covered by said doors. The two doors, therefore, meet at one edge of the trunk and when unfastened, open widely, exposing the interior very completely. One half of the outer walls of the trunk is thereby removed or opened. The holding elements 11 are then very accessible and can be swung around to wide open positions exposing both their sides, and hence the merchandise attached to them is in full view.

20 The slots 16 in the plates 14 and 15 permit both a rotary and a sliding movement of the pins 19 and 20 on the holding elements and for this reason the elements can be moved out to positions in which their inner edges will not interfere with each other, as would be the case if they were capable of rotary movement only without a bodily movement. In moving an element outwardly the user may first give it a slight lateral movement to cause the pins 19 and 20 to move out of the offsets 17. He is then able to move the element bodily in an edgewise manner to the full extent of the slot 16, after which he may give the said holding element a rotary movement to expose its inner face. In doing this he may first give the inner edge of the element a slight inward movement in order to move the pins 19 and 20 into the offsets 18 at the outer ends of the slots 16. When the pins are in these offsets the element can be given a rotary movement more conveniently. The offsets also tend to retain the inner edges in their outermost positions in relation to the slots 16 while succeeding elements are being manipulated. The tendency of the elements to slide back to their previous positions is prevented by the offsets 18.

50 While I have described my invention more or less precisely as regards the details of construction, I do not wish to be understood as limiting myself thereto, as I contemplate changes in form and the proportion of parts and the substitution of equivalents as circumstances may suggest or render expedient without departing from the spirit of my invention.

I claim:

60 1. The combination with a trunk, of a vertical holding element for merchandise carried within said trunk, means immovably secured within the trunk for supporting said holding element, means carried by said holding element at one vertical edge thereof re-

movably engaging said supporting means to permit a rotary and bodily movement of said holding element, and means for retaining said holding element vertically when in adjusted positions relatively to the trunk.

2. In a device of the character described, a containing element, a plurality of holding elements for merchandise carried by said containing element, hinge members in said containing element, hinge members on said holding elements adapted to engage said first named hinge members, and an elastic element on each holding element for yieldably holding said hinge members thereon in engagement with said first named hinge members.

70 3. In a device of the character described, a containing element, a plurality of holding elements for merchandise carried by said containing element, hinge members on said elements, and hinge members rigidly secured within said containing element removably engaged by said first named hinge members and adapted to permit a combined rotary and sliding movement thereof and also permit the detachment of the holding elements from the containing element.

75 4. In a device of the character described, a containing element, a plurality of holding elements for merchandise adapted to be carried in close relation in said containing element, guiding and retaining plates secured within the containing element adjacent the ends of said elements, and means adjacent one edge of each holding element removably engaging said plates to permit a rotary and a bodily movement of said elements.

80 5. A trunk for transporting and displaying samples consisting of a containing element having two vertically hinged sides, a plurality of vertical holding elements within said containing element for supporting merchandise, supporting means for said holding elements rigidly secured within said containing element immediately above and below said holding elements, said supporting means having slots of progressively greater length, and means adjacent one edge of the holding elements engaging the respective slots in the overlying and underlying supporting means to permit rotary and bodily movement of said holding elements, said bodily movement of the holding elements being progressively of different extent.

85 6. In a device of the character described, a containing element, a plurality of holding elements for merchandise carried by said containing element, guiding and retaining plates permanently secured within said containing element adjacent the ends of said elements having slots of progressively different lengths, and pivot members adjacent one edge of each of said holding

elements removably engaging said slots respectively and adapted to rotate and to slide therein.

7. In a device of the character described, 5 a containing element, a plurality of holding elements for merchandise carried by said containing element, pivot members on said elements, and hinge members comprising slotted plates in said containing element en- 10 gaging said pivot members and adapted to permit a combined rotary and sliding move- ment thereof, said slots having offsets at their ends into which said pivot members are adapted to enter.
- 15 8. In a device of the character described, a containing element, a plurality of hold- ing elements for merchandise carried by said containing element, guiding and re- taining plates adjacent the upper and lower 20 extremities of one edge of the holding ele- ments adapted to permit a rotary and a

bodily movement of each of said elements, and a supplementary supporting member bearing against the lower portions of said elements and spaced from the lower guid- 25 ing and retaining plate.

9. In a device of the character described, a containing element, a plurality of ver- 30 tical holding elements for merchandise car- ried by said containing element adjacent one vertical edge thereof, pivotal supports for said elements permitting a rotary and a bodily movement, and a supplementary sup- porting member beneath said elements spaced from the said pivotal supports. 35

In testimony whereof, I have subscribed my name.

ARTHUR DAVIS.
